UNITED STATES PATENT OFFICE.

WALTER S. MAYER, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

LIGHT-FOCUSING MECHANISM.

1,385,697.

Patented July 26, 1921.

Application filed September 9, 1918. Serial No. 253,278.

To all whom it may concern:

Be it known that I, WALTER S. MAYER, a citizen of the United States, residing in the city of Philadelphia, county of Philadelphia, and State of Pennsylvania, have invented 5 certain Improvements in Light-Focusing Mechanism, of which the following is a specification.

My invention is designed to provide improved supporting means of stable character 10 adapted for quickly, simply and accurately focusing a lamp with relation to a reflector, a primary object being to effect a desired universal movement by adjusting means 15 adapted to be supported in a desired manner.

The improved means comprise, in their preferred form, a frame provided with bearings adapted to be fixed to a support in various angular positions with relation to 20 its axis and the axis of the reflector, a lamp socket holder having trunnions adapted to rock and move axially said bearings with provision for passing conducting wires through a trunnion, means for moving and 25 setting said holder angularly, means for moving and setting said holder transversely to the plane of its angular movement and means for moving a lamp socket along the axis of said holder and for setting said 30 socket in the line of its axis in the intersection of said planes. The frame may be carried by various means as a plate back of the reflector or pedestal.

The nature of the improvements will be 35 fully understood from the following description and drawings of mechanism illustrating forms of the invention.

In the drawings, Figure 1 is an elevation of a form of mechanism embodying the invention with the supporting means and reflector shown in broken section; Fig. 2 is a rear elevation of the same with the reflector and supporting means removed; Fig. 3 is a bottom plan view of the structure shown in 40 Fig. 2; Fig. 4 is a broken front elevation of a modified construction embodying a supporting pedestal; Fig. 5 is a part sectional side elevation of the construction shown in Fig. 4, and Fig. 6 is a broken part sectional view taken through the axis of the lamp socket in illustration of details of the construction.

The mechanism as illustrated in Figs. 1, 2, and 3, comprises a skeleton frame or spider 1 which is provided with lugs 2, oppositely disposed alined bearings 3 in an axial plane thereof, and alined bearings 4 in a plane parallel to said axial plane. A support 5, conveniently a dished plate containing the aperture 5', has the part 1 fixed thereto by bolts 6 passing through the lugs 2 and the support.

A lamp socket holder 7 is provided with the trunnions 8 and 9, the former being journaled in one of the bearings 3 and the latter 65 having a threaded engagement with a nut 10 provided with a reduced cylindrical section 10' journaled in the bearing 3 the nut having the knurled head 10" for turning it to effect the lateral movement of the holder 70 along the axis of the trunnions. Journal caps 3' are hinged to the respective bearings 3, one adapted to be clamped against angular and lateral movement and the other being held against its bearings by the screw 75 11' and in engagement with the reduced section 10' of the nut 10 to prevent the longitudinal movement of the latter when turned.

A bolt 12 is fixed to a cross head or bar 12' which is journaled in the bearings 4. 80 This bolt has a threaded engagement with a nut 13 which is provided with a reduced cylindrical section 13' adapted to turn in a collar or bearing 14, the nut having a knurled head 13" for turning it.

The collar 14 has thereon a lug or shoulder 14' which is adapted to slide on a pintle 15 passing therethrough, the pintle being engaged in the yoke 16' on the holder 7 in parallel relation to the parts 8, 9 and 12'. 90

The holder 7, being released by retracting the screw 11, can be moved angularly by turning the nut 13 and transversely to the plane of its angular movement by turning the nut 10, the pintle 15 moving through the 95 part 14' in the lateral movement of the holder.

A bolt 16 is movable longitudinally in the holder 7 by a nut 17 which is journaled in the bearing 7', the bolt being pivotally connected through a pin 18 with the lamp socket 19. The socket 19 is telescoped in the holder 7 and movable longitudinally therein by turning the nut 17, the socket being pro-

vided with lugs 19' which are guided in ways 7" formed in the holder. A lock nut 20 engages the bolt 16 and is adapted for clamping the nut 17 to fix the socket 19, 5 and the lamp 21 carried thereby when the desired longitudinal adjustment has been effected.

The reflector 22, containing the axial opening 22' for the free movement of the socket holder 7, has the lamp 21 focused with relation thereto by the described universal adjustments, whereby the holder with the lamp held thereby is adapted to be oscillated, to be moved in a plane transverse to its 15 plane of oscillation, and to be adjusted along the intersection of said planes. The conducting wires 23 are connected to this lamp by the binding screws 24 and 24' and passed on opposite sides of the bolt 16 through the 20 hollow trunnion 8.

As illustrated in Figs. 4 and 5, the frame or ring 1' is provided with the concentric flanges 1^a and 1^b, the latter having the reduced portion 1^c and the shoulder 1^d. A 25 base 2' is fixed to the ring 1', and on a stand or pedestal 25 by bolts 26. A reflector 27 is provided at its apex with an opening 27' in which the part 1^c fits, the reflector bearing against the shoulder 1^d where it can be secured as by solder. An angle plate or brace 28 is secured to the reflector 27 and the base 2', being detachably engaged to the latter by a bolt 26.

The stand 25 carries the bolts 29 with the 35 sockets 30 thereon for holding ends of the wires 23, the bolts and sockets being electrically separated from the stand by the insulators 31 and electrical connections being made with the bolts through the binding 40 means 32 thereon.

As in the previously described construction, the lamp 21 is carried by a socket 19 which is movable longitudinally in the holder 7 by the action of the swiveled nut 17 on the bolt 16, the holder is rocked in the 45 bearings 3 by loosening the screw 11 and by turning the swiveled nut 13 on the bolt 12, and the revolution of the nut 10 on the trunnion 9 moves the holder laterally.

50 The wires 23 pass from the binding screws 24 and 24' through the hollow trunnion 8.

The socket 19 is provided with the resilient tongues 19^a, cut out of its threaded conducting shell 19'', which grip the lamp, and 55 with resilient tongue 19^b, connected with the binding screw 24', which presses against the rear of the lamp, whereby the latter is held firmly in its socket, the parts 19^a and 19^b being in circuit with the lamp filament.

60 Having described my invention, I claim,

1. In a light focusing device, the combination with bearing means, of a holder, means to have an oscillatory and longitudinal movement relative to said bearing means 65 whereby said holder is adapted to be moved

angularly about an axis, and transversely along said axis and means for moving said holder in a line transverse to said axis

2. In a light focusing device, the combination with bearing means, of a holder, means 70 for connecting said holder with said bearing means in turning relation and for adjusting it along the axis about which it turns whereby said holder can be oscillated in different parallel positions, and means for adjusting said holder transversely to said axis. 75

3. In a light focusing device, a bearing, lamp holding means having a laterally extending member, and a rotary coupling member connecting said laterally extending 80 member with said bearing, whereby said holder is adapted to be adjusted laterally along the axis of said member and angularly with relation to said axis.

4. In a light focusing device, a bearing, 85 lamp holding means having a laterally extending threaded member, and a coupling unit journaled relatively to said bearing and adapted to turn on said threaded member.

5. In a light focusing device, the combination with a frame provided with bearing means, of a holder provided with means connecting it with said bearing means in oscillatory and laterally movable relation, and means comprising a bolt connecting said 95 frame with said holder to adjust the latter angularly.

6. In a light focusing device, the combination with a frame provided with bearing means, of a holder provided with means connecting it with said bearing means in oscillatory and laterally movable relation, a lamp 100 socket movable longitudinally in said holder, and means comprising a threaded member connecting said holder and socket whereby 105 the latter is adjustable longitudinally.

7. In a light focusing device, the combination with a frame provided with bearings, of a holder having trunnions supported in journaled relation to said bearings 110 whereby it is adapted to oscillate, means for moving said trunnions longitudinally in relation to said bearings whereby said holder is adapted to be moved laterally, a lamp socket carried by said holder, and means for adjusting said lamp socket longitudinally. 115

8. In a light focusing device, the combination with a frame provided with bearings, one of said bearings comprising a nut journaled and held against longitudinal movement, of a holder having trunnions supported in journaled relation to said bearings, one of said trunnions having a threaded engagement with said nut, whereby said holder is movable laterally. 120

9. In a light focusing device, the combination with a frame provided with bearings, of a holder having trunnions supported in journaled relation to said bearings, means for moving said trunnions longitudinally 130

with relation to said bearings and means for fixing said holder in the position to which it is adjusted.

10. In a light focusing device, the combination with a frame provided with bearings, of a holder having trunnions journaled and movable longitudinally with relation to said bearings, a bolt connected in oscillatory relation to said frame, a nut engaging said bolt, and a pintle connected with said holder in parallel relation to said trunnions whereby said holder is adapted to rock and move laterally with relation to said nut.

11. In a light focusing device, the combination with a spider adapted to be clamped against a support, said spider having bearings thereon, of a holder extending through said spider, said holder having trunnions journaled and movable longitudinally with relation to said bearings, a lamp socket movable longitudinally in said holder, a bolt connected with said socket, and means connect-

ing said bolt with said holder for effecting the longitudinal movement therein of said socket.

12. In a light focusing device, the combination with a frame, of a holder having trunnions journaled on said frame, a lamp socket provided with terminals carried by said holder, and conducting means connected with a terminal or terminals aforesaid and passing through a trunnion aforesaid.

13. In a light focusing device, the combination with a frame, of a holder having trunnions journaled relatively to said frame, a lamp socket having resilient conducting means adapted for mechanically holding a lamp and making electrical connection with the lamp filament, and conducting means in circuit with said resilient conducting means and passing through one of said trunnions.

In testimony whereof I have hereunto set my name this 29 day of August, 1918.

WALTER S. MAYER.
